US0D1038042S

(12) **United States Design Patent** (10) **Patent No.:** **US D1,038,042 S**
(45) **Date of Patent:** **** Aug. 6, 2024**

(54) **WIRELESS LUMINAIRE CONTROLLER**

(71) Applicant: **Liteline Corporation**, Richmond Hill (CA)

(72) Inventor: **Daniel Silverstein**, Toronto (CA)

(73) Assignee: **Liteline Corporation**, Richmond Hill (CA)

(**) Term: **15 Years**

(21) Appl. No.: **29/854,427**

(22) Filed: **Sep. 23, 2022**

(30) **Foreign Application Priority Data**

Mar. 23, 2022 (CA) ..... CA 211353

(57) **CLAIM**

The ornamental design for a wireless luminaire controller, as shown and described.

DESCRIPTION

FIG. 1 is a perspective view of the front of the wireless luminaire controller;

FIG. 2 is a perspective view of the rear of the wireless luminaire controller;

FIG. 3 is a top plan view of the wireless luminaire controller;

FIG. 4 is a bottom plan view of the wireless luminaire controller;

FIG. 5 is an elevation view of the left side of the wireless luminaire controller;

FIG. 6 is an elevation view of the right side of the wireless luminaire controller;

FIG. 7 is an elevation view of the upper end of the wireless luminaire controller; and,

FIG. 8 is an elevation view of the lower end of the wireless luminaire controller.

1 Claim, 4 Drawing Sheets
